his Atty's.

UNITED STATES PATENT OFFICE.

ALFRED M. LANE, OF ST. LOUIS, MISSOURI, ASSIGNOR TO MONARCH METAL PRODUCTS COMPANY, OF ST. LOUIS, MISSOURI, A CORPORATION OF MISSOURI.

METAL WINDOW-SCREEN.

1,350,027.

Specification of Letters Patent. Patented Aug. 17, 1920.

Application filed August 21, 1919. Serial No. 318,878.

To all whom it may concern:

Be it known that I, ALFRED M. LANE, a citizen of the United States, and a resident of the city of St. Louis and State of Missouri, have invented a new and useful Improvement in Metal Window-Screens, of which the following is a specification.

My invention relates to metallic window screens. Heretofore, window screens have been made with metal frames; but they have been subject to divers disadvantages. The more common disadvantages are that the frames are more or less flimsy in construction or else they are unnecessarily expensive; many of them are of more or less unsightly appearance; and usually it is quite difficult or impracticable to replace the wire cloth. The object of the present invention is to overcome these disadvantages and to produce a screen of neat appearance, adapted for economic manufacture, of great strength and rigidity and well adapted for repair and replacement of parts. It consists in the parts and in the combinations of parts hereinafter described and claimed.

In the accompanying drawing, which forms part of this specification, and wherein like numerals refer to like parts wherever they occur,

30 Figure 1 is a view of a corner portion of a screen embodying my invention with parts broken away;

Fig. 2 is a cross-section on the line 2—2 in Fig. 1;

35 Fig. 3 is a cross-section, similar to Fig. 2, showing a special hinge member incorporated in the frame;

Fig. 4 is a similar cross-section through the side of the frame showing a modification 40 of the frame members to constitute a guideway for coöoperating with the guide strip on the window frame;

Fig. 5 is a similar cross-section through the side portion of the frame showing a 45 modification wherein one of the frame members is formed into a guideway;

Fig. 6 is a cross-section showing a modification wherein a separate locking strip is used between the main frame members; and

50 Fig. 7 is a detail view of a corner bracket or reinforcing member.

The frame of my screen comprises inside

members A and outside members B. detachably secured together, preferably by screws 13, with the wire fabric or meshwork 14 interlocked or engaged between them. Preferably the frame members are straight pieces mitered at their ends and held together by means of corner pieces 15 provided for the purpose.

The frame members are preferably of the cross section illustrated in Figs. 2 and 3. In the construction illustrated in said figures, the inside frame member A is a strip of sheet-metal bent endwise in such manner as to form a hollow boxing. For this purpose, the longitudinal marginal portion of said strip is folded back to lie flatwise against the adjacent portion of the strip and thereby stiffen it and adapt it to constitute the outer end wall 16 of the boxing. The inner side wall 17 of the boxing, constituting the inner face of the frame, is a substantially plane surface disposed more or less perpendicularly to said outer end wall. The third 70 or inner end wall 18 of the boxing is substantially perpendicular to the inner side wall thereof and is preferably slightly narrower than the outer end wall. The fourth wall 19 or outer face of the boxing is of 80 irregular form especially designed to co-operate with the other parts of the device. Where the fourth side, being the outer face of the boxing, joins the third side, it has a convex curve that is continued inwardly 85 substantially parallel with said third side and thence is continued in a more or less semi-circular curve, thus forming a hook portion 20 at the inner end wall of the frame and a socket or groove 21 adjoining the same. From this socket, the said fourth side of the boxing extends for a distance substantially parallel with said second side and thence is formed into a terminal loop 22 of 90 proper length to bear against the corner portions of the first and second walls of the boxing and constitute a brace. The end portion of the terminal loop is spaced from the first or outer end wall of the boxing to form a groove or recess 23 for coöperation with 95 the outer coöoperating member of the frame. The end portion of the terminal loop is spaced from the first or outer end wall of the boxing to form a groove or recess 23 for coöperation with 100 the outer coöoperating member of the frame. By reason of the section above described, not only is the main body portion of the boxing hollow, but sufficient space is left

100

between said fourth side and the second and third sides to receive the corner bracket or reinforcing member 15 hereinafter described. In practice, it is desirable to solder the terminal loop to the outer end wall of the boxing at their line of contact, as illustrated at 24. The resulting boxing is of great strength and furnishes two longitudinal grooves or recesses in the outer face, together with such resiliency as may be desirable therefor; and at the same time, it affords a convenient way of neatly and tightly securing the parts together.

The wire cloth 14 or other suitable mesh-work has grooves or hollow ribs rolled or otherwise formed adjacent to its margins, preferably by rolling the same prior to assembling. These marginal ribs in the wire cloth are about the same width but preferably slightly shallower than the grooves in the boxing into which they are fitted and wherein they are held by means of ribs 25 on the outer members of the frame.

Each of the outer frame members B comprises a strip of sheet-metal folded flatwise to form a double thickness. Near the inner edge of the outer frame member, its inner ply is bent to form a rib 25 in position to enter and coöperate with the inner groove of the boxing; while the outer marginal portion of said outer frame member is bent inwardly to form a rib 26 in position to engage and coöperate with the outer groove or recess 23 provided therefor in said boxing. Preferably the outer ply of said outer member is formed into a loop 27 that completely incloses the terminal flange of the inner ply and the parts are soldered together as indicated at 28 to make the outer member stiff and strong.

The inner and outer members A and B of the frame are preferably secured together by means of screws 13 that pass through countersunk holes formed therefor in the outer member and punched or threaded holes in the middle portion of the outer side of the boxing. The inner ends of the screws are concealed within the boxing, while the exposed heads of the screws lie flush with the outer surface of the frame.

At the corners, the frame members are joined together by means of corner brackets or reinforcing members 15. These corner brackets are preferably made of heavy sheet-metal forged or otherwise formed into the sectional shape illustrated in Fig. 2; that is, of a shape to fit in the hollow of the boxing and follow the inner surface of the outer side wall thereof.

Threaded holes 29 are formed through said corner brackets to receive threaded screws 30 that pass through countersunk holes in the outer frame member and through the outer wall of the boxing. Preferably, the surface of the corner bracket is

grooved or depressed around the threaded hole for the purpose of receiving solder intended to hold the parts together as indicated at 31. Likewise, solder is preferably used in the angle between the inner lip or flange of the corner bracket and the bottom wall of the socket or inner groove in the boxing.

It is noted that, when the parts are secured together, the frame presents a very neat appearance and is very stiff and strong. As the parts in contact with the wire cloth have their corners rounded, there is very little danger of tearing the cloth; and when the cloth requires replacement, it is only necessary to disengage the screws and separate the frame members, whereupon the old cloth can be removed and replaced with a new cloth, after which the frame members can be reassembled and secured.

In the modification illustrated in Fig. 3, a hinge or mounting member 32 is secured to the frame. This hinge or mounting member comprises a sheet of metal rebent to form a loop that straddles the doubled edge of the outer wall of the boxing, the inner edge of said loop being flanged in position for the outer rib 26 of the outer frame member to bear against, and the outer marginal portion of said loop being formed into an eye 33 or otherwise adapted for coöperation with its counterpart mounting member.

In the modification illustrated in Fig. 4, the inner wall of the boxing is extended beyond the outer end wall thereof to form a doubled rib 34 for coöperation with a guide-rail. In the same design, the complementary guide rib 35 is mounted in the outer socket of the boxing, this last mentioned rib consisting of a doubled sheet of metal whose inner portion is formed into a socket that fits in the outer groove of the boxing in position to coöperate with the outer rib of the outer frame member. For convenience of mounting and dismounting the screen, the outer guide rib 35 is preferably wider than the inner guide rib 34, as illustrated in Figs. 4 and 5.

In the modification illustrated in Fig. 5, both guide ribs 34^a and 35^a are formed integral with the boxing. It is noted that, in this design, the outer frame member terminates flush with the inner face of the inner rib, whereas in the other designs, the inner margin of said outer frame member extends inwardly beyond said rib and serves the twofold purpose of clamping the wire cloth and making a neater appearance.

In the modification illustrated in Fig. 6, the inner rib of the outer frame member is replaced with a groove 36 adapted to receive a locking bar or member 37 that, in a general way, serves the purpose of the guide rib.

Obviously, the construction hereinbefore

described admits of considerable change and I do not wish to be restricted to the details described.

What I claim is:

5. 1. A screen comprising inner and outer frame members and meshwork locked between them, one of said frame members comprising a strip of metal bent lengthwise to form a closed hollow boxing of substantially quadrilateral section with longitudinal grooves in its inner side, and the opposing frame member comprising a strip of metal provided with stiff longitudinal ribs adapted to coöperate with the grooves of said first mentioned member.
2. A screen comprising inner and outer frame members and mesh work locked between them, one of said frame members comprising a strip of metal bent lengthwise to form a closed hollow boxing of substantially quadrilateral section with three substantially plane sides and with a fourth side provided with longitudinal grooves, and the opposing frame member comprising a strip of metal provided with stiff longitudinal ribs adapted to coöperate with the grooves of said first mentioned member.
3. A screen comprising inner and outer frame members and meshwork locked between them, one of said frame members comprising a strip of metal bent lengthwise to form a hollow boxing of substantially quadrilateral section with three substantially plane sides and with a fourth side provided with longitudinal grooves, and the opposing frame member comprising a strip of metal doubled lengthwise and having its inner ply provided with longitudinal ribs adapted to coöperate with the grooves of said first mentioned member.
4. A screen comprising inner and outer frame members, one of said frame members comprising a strip of metal bent lengthwise to form a hollow boxing with longitudinal grooves in one side, and the opposing frame member comprising a strip of metal provided with longitudinal ribs adapted to coöperate with the grooves of said first mentioned member, a meshwork locked in one of said grooves, and a mounting member locked in the other groove.
5. A screen comprising inner and outer frame members and meshwork locked between them, one of said frame members comprising a strip of metal bent lengthwise to form a hollow boxing with a rib projecting from the end wall thereof and with a longitudinal recess for the meshwork in one side wall.
6. A screen comprising top, bottom and side members constituting a frame of which the side frame members comprise sheet-metal strips provided with parallel guide ribs of unequal width projecting outwardly from the end walls thereof.
7. A screen comprising top, bottom and side members constituting a frame, of which the side frame members comprise a hollow boxing of sheet-metal provided with parallel guide ribs of unequal width integral therewith and projecting outwardly from the end walls thereof.
8. A screen comprising a hollow boxing having a longitudinal groove in one side wall for the meshwork and longitudinal ribs projecting unequal distances from one end wall to form guide ways, meshwork and means for securing said meshwork to the boxing.
9. A screen comprising inner and outer frame members and meshwork locked between them, one of said frame members comprising a strip of metal bent lengthwise to form a hollow boxing, one side of which is provided with a groove for the meshwork, said other frame member being provided with a rib for locking the meshwork in said groove, the ends of the frame members being mitered, corner members fitting in the hollow of the boxings and means for securing said parts together, said securing means being invisible on the boxing side of the screen.
10. A screen comprising inner and outer frame members and meshwork locked between them, one of said frame members comprising a strip of metal bent lengthwise to form a hollow boxing, one side of which is provided with a groove for the meshwork, said other frame member being provided with a rib in position to lock the meshwork in said groove, corner members fitting in the hollow of the boxings and means for securing said parts together, said securing means extending through the outer frame member, corner member and outer wall of the boxing and terminating in the hollow thereof so as to be invisible on the boxing side of the screen.
11. A screen comprising inner and outer frame members and meshwork locked between them, one of said frame members comprising a strip of metal bent lengthwise to form a hollow boxing, one side of which is provided with a groove for the meshwork and with a brace loop adapted to bear against the inside of the corner portion of the boxing and to form a marginal recess, and a supplemental member fitting in said last mentioned recess, said other frame member being provided with ribs in position to enter said groove and recess and thereby lock the meshwork and said supplemental member.
12. A screen comprising inner and outer frame members and meshwork locked between them, one of said frame members comprising a strip of metal bent lengthwise to form a hollow boxing, one side of which is provided with a groove for the

- meshwork and with a brace loop adapted to bear against the inside corner portion of the boxing and to form a marginal recess, and a supplemental member fitting in said recess, said other frame member being provided with ribs in position to enter said groove and recess and thereby lock the meshwork and said supplemental member, the ends of the frame members being mitered, 10 and corner members fitting in the hollow of the boxing members and means for securing said corner members and frame members together, said securing means being invisible on the boxing side of the screen.
- 15 13. A screen comprising inner and outer frame members and meshwork locked between them, one of said frame members comprising a strip of metal bent lengthwise to form a hollow boxing, the outer face of 20 said boxing being bent to form a brace loop arranged to bear against the inside of the corner portion of the boxing.
14. A screen comprising inner and outer frame members and meshwork locked between them, one of said frame members comprising a strip of metal bent lengthwise to form a hollow boxing, the outer face of 25 said boxing being bent to form a brace loop which is soldered to the corner portion of the boxing.
- 30 15. A screen comprising inner and outer frame members and meshwork locked between them, one of said frame members comprising a strip of metal bent lengthwise to form a quadrilateral hollow boxing, the portion of said strip constituting one side of said boxing being bent to form a groove for the meshwork and to form a brace loop in position to engage the inside of the corner portion of said boxing, the terminal portion of said brace loop being spaced from the end wall of said boxing and forming therewith an intervening recess with one resilient side. 35
16. A screen comprising inner and outer frame members and meshwork locked between them, one of said frame members comprising a strip of metal bent lengthwise to form a quadrilateral hollow boxing, the portion of said strip constituting one side 40 of said boxing being bent to form a groove for the meshwork and to form a brace loop soldered to the corner portion of said boxing, the terminal portion of said brace loop being spaced from the end wall of said boxing, and forming therewith a recess with 45 one resilient side.
17. A screen comprising inner and outer frame members and meshwork locked between them, one of said frame members comprising a strip of metal bent lengthwise to form a hollow boxing, the marginal portion of the outer face of said boxing being soldered to the inside of the corner portion 50 of the boxing. 55
- Signed at St. Louis, Missouri, this 19th day of August, 1919.
- ALFRED M. LANE.
